EXHAUST TUBE CRACK-OFF DEVICE

Arthur P. Russell, Maple Heights, and John H. Hollopette, Mayfield Heights, Ohio, assignors to General Electric Company, a corporation of New York

Application October 30, 1951, Serial No. 253,922

3 Claims. (Cl. 49—48)

1

Our invention relates to apparatus for cracking-off an excess end portion of a vitreous exhaust tube extending from a mount for a lamp, radio tube or other electrical device of similar construction. Our invention relates in particular to automatically operated apparatus for cracking-off an end section of an exhaust tube extending from a stem of the so-called "tipless" type and constituting the main supporting element of mounts used in incandescent and fluorescent lamps and many other electrical devices.

The cathode mount for fluorescent lamps, for instance, is manufactured by a method and means whereby an exhaust tube of relatively long length is required on the stem tube of the mount. However, midway in the manufacture of the fluorescent lamp an exhaust tube of such a long length is no longer required and, in fact, is objectionable in that it is easily broken and in that it projects from the end of the fluorescent lamp, making the handling thereof more difficult. Damaged and broken exhaust tubes prevent the proper coupling of manufacturing apparatus to the lamp and require a lamp damaged in this manner to be discarded.

One object of our invention is to provide apparatus for cracking-off an excess end portion of a vitreous exhaust tube extending from a stem of a mount and to effect the crack-off in a manner causing a clean break across the exhaust tube at a definite position along its length. The apparatus removes the excess portion of the exhaust tube not required in subsequently occurring manufacturing operations and produces a cut end on the remaining end of said tube on the mount which renders it suitable for connection to other manufacturing apparatus and, at a later interval, to be sealed or tipped-off.

Another object of our invention is to provide effective and relatively inexpensive automatically operating apparatus for cracking-off an end portion of an exhaust tube extending from the vitreous stem of a mount, the apparatus being particularly suited to be incorporated in existing lamp making apparatus and to effect the crack-off of the exhaust tube while the mount is retained by the relatively flexible chain type conveyor of said apparatus. In a preferred embodiment of the invention, the mounts are carried during the course of their manufacture to means for scoring the exhaust tubes at the crack-off point and are then carried to operative relation to means for applying a bending force to said exhaust tubes to cause said tubes to crack-off. The latter operation occurs at a time when the

5 mounts are retained in heads of a chain type conveyor and, because of the construction of said heads, are adapted to be tilted to a wedged position wherein pressure against the exhaust tubes of the mounts can create tension in the scored area thereof.

Other objects and advantages of our invention will appear from the following detailed description of a species thereof and from the drawing.

10 In the drawing, Fig. 1 is a plan view of adjacent portions of two interconnected conveyors in respective ones of which the exhaust tube scoring and crack-off means of the invention are incorporated; Fig. 2 is a side elevation of the end portion of the conveyor comprising the crack-off means, the view being modified by the removal of the near side of the conveyor chain to more clearly show said crack-off means; Fig. 3 is a perspective view, on a larger scale, of one of the 15 heads of the crack-off conveyor and adjacent portions of the chain and supporting rails therefor; and Fig. 4 is a perspective view of the actuating means and the associated support means at the end of the conveyor opposite from the crack-off means.

25 Referring to Fig. 1 of the drawing, the scoring operation, which is the first step in the removal of an excess end portion of an exhaust tube of a mount, is shown as occurring at station A along a mount conveyor 1, whereas the crack-off operation, which completes the removal of said excess portion, is shown occurring at station C along a second mount conveyor 2 carrying the mount in a subsequent interval in the manufacture. The station A and the following station B represent work stations to which the mount 3 is indexed in the course of movement of the mount conveyor 1 of cathode mount making apparatus of the type disclosed in Flaws Patent

30 2,380,742 dated July 31, 1945, and assigned to the assignee of the present invention. The mount 3 is retained at all stations of both conveyors 1 and 2 in an inverted position as shown in Fig. 2 with the vitreous exhaust tube 4 projecting upwardly from the flared vitreous stem tube 5 and with the cathode assembly 6 located directly below the stem tube 5. The scoring operation takes place at station A of conveyor 1 when the sharp edged metal disc 7 on the spindle 8 of a 35 high speed electric motor 9 is moved against a portion of the exhaust tube 4 for an instant and causes a notch or score 10 (Fig. 2) to be made therein at a point adjacent the flared rim 11 of the stem tube 5.

40 45 50 55 No further operations relating to the present

invention occur until the mount 3 is advanced to station B of conveyor 1 at which station said mount 3 is transferred into one of the heads 12 of the chain type conveyor 2. The transfer is effected at the limit of an end-foremost translational movement of the conveyor 2 (which is for the most part representative of a conveyor disclosed in the aforesaid Flaws Patent 2,380,742) when a head 12, then located at the end of the conveyor 2, is advanced to an extent that the jaws 13 and 14 are in gripping relation to the exhaust tube 4 and the tines of the forked or bifurcate end of the holder 15 (Figs. 2 and 3) are under the flared rim 11 of the stem tube 5. The release of the mount 3 by the conveyor 1 completes the transfer operation when said mount 3 drops slightly so that the flared rim 11 of the stem tube 5 comes to rest upon the holder 15.

The next step in the operation of the apparatus is a retraction of the conveyor 2 bodily to the right to the position it appears in Fig. 1 and is the result of corresponding movement of the sprockets 16 and 17 at the end turns of the chain 18 supporting the heads 12. The retraction movement also effects an indexing movement of the conveyor 2 to carry the heads 12 in a clockwise direction (Fig. 1) thereabout and, accordingly, advances a head 12 containing a mount 3 away from the end position thereof while an empty head 12 is advanced thereto. The index is brought about by the relation of the sprocket 16 and the support shaft 19 therefor and occurs when the movement of the conveyor 2 causes the relative movement produced in the arm 20 and pawl 21 to turn the ratchet wheel 22 on a lower portion of the shaft 19. The arm 20, which is connected through bar 23 to a stationary part of the apparatus and which is pivoted on the shaft 19, pulls the pawl 21 back around the ratchet wheel 22 to another notch therein during the advance of the conveyor 2 and, accordingly, does not cause the chain 18 to be indexed at such times.

During the passage of the heads 12 along the straight runs of the conveyor 2, the chain 18 is guided in its direction of travel by the rails 24 and 25 on opposite sides of each run, and the mount holders 15 slide along the top surfaces of said rails 24 and 25. A bracket-shaped member 26, of which the holder 15 is a part, provides the support for the exhaust tube retaining jaws 13 and 14 which are pivoted upon the bolt 27 and which are closed against the exhaust tube 4 by the contraction force of a spring 28 extending between ears on the jaws. A tongue 29 on the bracket 26, and between the jaws 13 and 14, centers said jaws 13 and 14 over the stem tube 5 of the mount 3 and the holder 15. The opposite ends of the conveyor 2 are caused to advance and retract correspondingly since the opposite ends of the guide rails 24 and 25 are fastened to the movable support 30 (only partially shown) for the sprocket 16 and shaft 19 at the loading end thereof and to the movable support 31 for the sprocket 17 and the shaft 32 at the opposite end thereof. As shown in Fig. 2, the support 31 is restricted to a definite path of movement by the engagement of the rollers 33 and 34 thereon with the top surface and a channel way, respectively, in the block 35 of the bracket 36 on the upper end of the fixed standard 37.

The translational movement of the conveyor or carrier 2 may be effected by actuation of the assembly of rails 24, 25 and supports 30, 31 by cam actuated means (Fig. 4) comprising a cam

50 which may be mounted on the drive shaft 51 of the conveyor 1. A cam follower lever 52 is actuated by the track 53 in cam 50 through a roller 54 at one end thereof, and is pivoted about a stationary shaft 55 to actuate a link 56 connected to support member 30 to impart the translational movements thereto in proper timed sequence with actuation of the conveyor 1.

The crack-off operation of the invention occurs during the advancing translational movement of said conveyor 2 toward the loading position when the head 12 at station C is carried toward an abutment or crack-off member in the form of the stationary finger 38 to press the upper end portion of the exhaust tube 4 against said finger 38. The advancing motion in the conveyor 2 brings the end of the stationary finger 38 against the side of the exhaust tube 4 containing the notch or score 10 (Fig. 2) and now facing toward the center of the conveyor 2 as against its opposite position in the first conveyor 1, and produces a bending pressure against said exhaust tube 4 which applies a rupturing strain in the notched area.

20 The success of the operation is dependent upon proper wedging of the mount 3 at a fixed position in the holder 15 during the initial moments of the movement of the exhaust tube 4 against the finger 38 when the mount 3 is tilted thereby to an extent that the rim 11 of the stem tube 5 seats against the overhanging lip 39 of the holder 15. The pressure of the finger 38 against the upper end portion of the exhaust tube 4 first forces said exhaust tube 4 from between the jaws 13 and 14 and then tilts the mount 3 to an extent that the rim 11 of the stem tube 5 is forced against the lip 39 of the holder 15 and the supporting legs 40 for said lip 39. All portions of the holder 15 remain in fixed position during the crack-off operation since the back edge 41 of the lip 39 bears against an ear 26' on the upstanding portion of bracket 26 of the holder 15 and said bracket 26 is backed by the shoulder 42 of the collar 43 on the sprocket shaft 32 at such times. The sudden break of the exhaust tube 4 throws the free end portion thereof out from the mount 3 to a position where it falls clear of all portions of the apparatus and the mount 3 is prevented from jarring out of the holder 15 by a stationary guard 44 located opposite the stem tube 5 at a position adjacent the end of said holder 15.

Inasmuch as the lip 39 must be of a size to match the flared stem tube 5 of the mount 3 and must be replaced with another of different size if a mount 3 having a different stem tube is being handled, said lip 39 is provided with legs 40 which can be sprung outward to separate it from the holder 15. Means are also provided in the apparatus to render the crack-off means inoperative, a condition which is sometimes desirable. Said means is in the form of a hinge pin 45 on the supporting arm 46 for the finger 38 and allows said finger 38 to be swung back to a rest position on the support arm 46. In its normal position, the finger 38 rests upon the extending end portion 47 of the support arm 46 and remains at a fixed position since the rod 48 holding the support arm 46 is mounted in the bracket 36 on the end of the support standard 37.

70 Although a preferred embodiment of the invention has been described specifically, it will be understood that the invention is not limited to the specific construction and arrangement of parts shown, but that they may be modified with-

in the spirit and scope of the invention as defined in the appended claims.

What we claim as new and desire to secure by Letters Patent of the United States is:

1. In combination, a conveyor comprising an endless chain carrying a plurality of holders each having a horizontal bifurcate portion adapted to support the flared upper end of a stem tube of a mount having an exhaust tube projecting upwardly therefrom, each of said holders also including a horizontal overhanging lip portion above and to the rear of said bifurcate portion so as to overlie a portion of the rim of the flared end of a stem tube in said holder, means to effect translational motion of said conveyor to advance it toward and retract it away from a loading position, means to index said chain about the conveyor during the retraction of the conveyor, an abutment finger means located above one of the positions occupied by said holders and in the path of movement of the upper end of an exhaust tube of a mount carried by the holder at said one position during the advancing translational movement of the conveyor to first cause the mount to be tilted and its flared end wedged in its holder against the said lip portion thereof and to then cause the exhaust tube to be bent and cracked off.

2. In apparatus of the class described, a carrier, a plurality of stem holders mounted at the periphery of said carrier, each of said stem holders comprising a generally U-shaped bracket member arranged with its legs extending horizontally and one above the other and projecting outwardly from the carrier, the lower leg of said bracket being slotted at its free end to receive a lamp stem having a flared upper end rested on said lower leg and also having a glass exhaust tube projecting from said stem upwardly beyond said flared end, a pair of spring-closed jaws mounted on the upper leg of said bracket and aligned with the slot in said lower leg to resiliently grip the said exhaust tube, and a wedge member in the form of a readily-detachable clip secured to said lower leg and having a horizontal body portion spaced above said lower leg to be just above the flared upper end of the stem in said holder and abutting against the upstanding portion of said bracket which connects said legs, said body portion having deformable leg portions extending downwardly from opposite sides thereof and shaped to clip onto opposite sides of the lower leg of said bracket to the rear of the said slot therein, an abutment finger means located adjacent the path of movement of the holders and inwardly of the periphery of said carrier, and

means to effect relative horizontal movement of a holder and said abutment means to bring the exhaust tube of a stem in said holder into engagement with said abutment means to first tilt the stem so that its flare becomes wedged between the said lower leg of the holder and said wedge member and to crack off the said exhaust tube upon continuation of said relative movement.

3. In apparatus of the class described, a carrier, a plurality of stem holders mounted at the periphery of said carrier, each of said stem holders comprising a generally U-shaped bracket member arranged with its legs extending horizontally and one above the other and projecting outwardly from the carrier, the lower leg of said bracket being slotted at its free end to receive a lamp stem having a flared upper end rested on said lower leg and also having a glass exhaust tube projecting from said stem upwardly beyond said flared end, a pair of spring-closed jaws mounted on the upper leg of said bracket and aligned with the slot in said lower leg to resiliently grip the said exhaust tube, and a wedge member in the form of a readily-detachable clip secured to said lower leg and having a horizontal body portion spaced above said lower leg to be just above the flared upper end of the stem in said holder and abutting against the upstanding portion of said bracket which connects said legs, said body portion having deformable leg portions extending downwardly from opposite sides thereof and shaped to clip onto opposite sides of the lower leg of said bracket to the rear of the said slot therein, an abutment finger means located adjacent the path of movement of the holders and inwardly of the periphery of said carrier, and means to effect a horizontal translational movement of said carrier in a direction to bring the exhaust tube of a stem in one of said holders into engagement with said abutment means to first tilt the stem so that its flare becomes wedged between the said lower leg of the holder and said wedge member and to crack off the said exhaust tube upon continuation of said translational movement of the carrier.
